ELECTRIC SWITCH

George R. Brown, Stratford, Conn., assignor to
 General Electric Company, a corporation of
 New York

Application January 2, 1936, Serial No. 57,104

8 Claims. (Cl. 200—156)

The present invention relates to electric switches of the pull operated type and particularly to switches of this type having liquid contact circuit closers for controlling the flow of current.

5 The object of my invention is to provide an improved construction and arrangement in switches of this type, and for a consideration of what I believe to be novel and my invention attention is directed to the accompanying description and the claims appended thereto.

10 In the accompanying drawing, Fig. 1 is a front elevation of a switch embodying my invention with part of the casing removed in order more clearly to show the construction; Fig. 2 is a sectional end elevation of the switch; Fig. 3 is a fragmentary front elevation of the lower end of the switch showing the position of the pull member at the start of its return movement after 15 moving the switch from one circuit controlling position to a succeeding circuit controlling position; Fig. 4 is a view showing the construction and operation of the liquid contact circuit closer; and Fig. 5 is a sectional view taken on line 5—5 20 of Fig. 1.

25 Referring to the drawing, I have illustrated my invention using a liquid contact circuit closer having a pair of cup-shaped metal terminals 1 which are separated by an insulating diaphragm 2 of a refractory material such as a ceramic material. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the circuit closer the space enclosed by the terminals is evacuated and filled with hydrogen at a pressure of one or more atmospheres which increase the current interrupting capacity of the circuit closer. As shown by the full lines in Fig. 4, the diaphragm 2 is provided with an opening 5 which is submerged in the mercury when the circuit closer is in the 30 current conducting position. When the circuit closer is in the current interrupting position shown in dotted lines in Fig. 4, the opening 5 is above the mercury, and the circuit between the terminals is therefore broken by the insulating diaphragm 2. Due to the construction of the circuit closer, the interrupting of the circuit between the terminals takes place in the mercury as the circuit closer is turned so that the opening 5 is lifted clear of the mercury. The above 35 described construction is illustrative of liquid

contact circuit closers which are suitable for use in a switch embodying my invention.

The switch is enclosed within a housing comprising complementary parts 6 and 7 of molded insulating material which are secured together 40 by clamping straps 8 and 9. The clamping strap 8 is provided with ears 10 for mounting the switch.

The liquid contact circuit closer is supported for rotation about its axis by contact strips 11 45 having projections 12 which fit into depressions 13 formed in the terminals 1 of the circuit closer. The projections 12 on the contact strips and the depressions 13 in the terminals provide ball and socket connections for supporting the switch for 50 rotation about its axis and also for conducting electricity to the terminals. During the rotation of the circuit closer, the wiping action between the terminals and the contacts keeps the contact surfaces clean and tends to prevent increase of contact resistance. The contact strips 11 are secured to the part 6 of the housing by the spun-over portions 14 of inserts 15 molded in the housing. The line conductors are connected to the contact strips by means of terminal 55 screws 16 threaded into the inserts. The circuit closer is rotated by means of a ring 17 of insulating material which is keyed to the terminal which faces the part 7 of the housing by means of a tongue 18 which fits into a depression in the 60 terminal. One of the contact strips 11 overlaps the outer edge of the ring 17 and holds it on the terminal.

The part 7 of the housing is provided with a boss 19 concentric with the circuit closer which 65 is provided with a slot 20 in which is secured one end of a spiral spring 21. The free end of the spiral spring is fixed to a pin 22 which projects over the periphery of the ring 17. A pull chain 23 is attached to the pin 22 by means of 70 a plate 24 which is pivoted on the pin 22 and which is provided with a tongue 25 having a slotted end which fits between adjacent balls of the chain. A sheet 25a of insulating material prevents contact of the spring 21 and the chain 75 23 with the adjacent contact 11. The chain extends through an opening 26 in the lower end of the housing which is formed by complementary grooves in projections 27 and 28 on parts 6 and 80 7 of the housing. The projections 27 and 28 project through an opening 28a in the strap 9 and thereby center the switch in the clamping straps.

When the switch is in the position shown in Fig. 1, a pull on the chain causes the pin 22 to 85

move between the ring 17 and the upper end of a barrier 30 into one of the notches 29 formed in the ring 17 and thereby to rotate the liquid contact circuit closer. The barrier 30 is formed on the 5 part 6 of the housing and surrounds substantially half the periphery of the ring 17. Its function is to prevent movement of the pin 22 from the notch 29 while the pin is between the barrier 30 and the periphery of the ring 17. If the chain is 10 released while the pin 22 is in this position, the coil spring causes the ring 17 and the circuit closer which is keyed thereto to be returned to the position shown in Fig. 1. This prevents the circuit closer remaining in positions less than 180° apart. After the circuit closer has been turned 15 through 180° the pin 22 moves from the notch 29 and passes through a passage 31 formed between the lower end of the barrier 30 and a raised portion 32 on the housing 6. When the chain is 20 released after the pin 22 has been moved below the lower end of the barrier 30, the coil spring 21 causes the pin to be moved to the outside of the barrier as shown in Fig. 3 and returned along the outside of the barrier to the position shown in 25 Fig. 1. This switch operating mechanism will therefore rotate the liquid contact circuit closer through only a half revolution at each operation. At the end of one half revolution of the circuit closer, the opening 5 in the diaphragm 2 of the 30 circuit closer is in the full line position shown in Fig. 4 and the circuit closer is in its current conducting position. At the end of the other half revolution of the circuit closer, the opening 5 is in the current interrupting position shown in dotted lines in Fig. 4.

What I claim as new and desire to secure by Letters Patent in the United States is:

1. In combination, a liquid contact circuit closer supported for rotation, pull operated means 40 biased to an initial position, a connection between the circuit closer and pull operated means effective when the pull operated means is in its initial position whereby the circuit closer is rotated away from and back to its initial position 45 in accordance with movement of the pull operated means, and means for effecting release of said connection upon a predetermined rotation of the circuit closer whereby the circuit closer is independent of subsequent movement of the pull operated means toward and away from its initial 50 position.

2. In combination, a rotatable member, pull operated means biased to an initial position and having a part adapted to engage and rotate said member, a barrier for holding said part in engagement with said member during a predetermined rotation of said member, and means including a passage to the outside of said barrier through which said part is moved for releasing 60 the connection between said part and said member whereby said member is independent of subsequent movement of the pull operated means toward and away from the initial position.

3. In a pull switch having parts movable to 65 circuit controlling positions, operating mechanism for moving said parts to successive circuit controlling positions including a rotatable member, pull operated means having a part adapted to engage said member and thereby positively 70 rotate said member in either direction, means for returning said pull operated means to its initial position, means for disengaging said part from said member when the switch reaches a succeeding circuit controlling position whereby the pull operated means is returned to its initial position

without affecting the rotatable member, and means for holding said part in engagement with said member whereby upon release of the pull operated means prior to reaching the succeeding circuit controlling position said member is positively returned by the pull operated means to the preceding circuit controlling position. 5

4. In a pull switch having parts movable to circuit controlling positions, operating mechanism for moving said parts to successive circuit controlling positions including a rotatable member, a coil spring arranged on the axis of said member and having a pull member attached to the free end thereof, said pull member having a part adapted to engage said rotatable member and thereby rotate said member, means including a barrier for holding said part in engagement with the rotatable member until the rotatable member has moved said switch to a succeeding circuit controlling position whereby upon release of the pull member prior to reaching the succeeding circuit controlling position the rotatable member is returned by the pull member to the preceding circuit controlling position, means including said spring for moving said pull member from between said barrier and said rotatable member when the switch has been moved to said succeeding circuit controlling position and for returning said pull member to its initial position. 20 25

5. In a pull switch having parts movable to 30 circuit controlling positions, operating mechanism for moving said parts to successive circuit controlling positions including a rotatable disk having symmetrically arranged stops on the periphery thereof, pull operated means having a part 35 adapted to engage one of said stops and rotate said disk, means for returning the pull operated means to its initial position, means including a barrier for holding said part in engagement with said stop until said member has moved the switch 40 to a succeeding circuit controlling position whereby upon release of the pull operated means prior to reaching the succeeding circuit controlling position the disk is returned by the pull operated means to the preceding position, and means for 45 releasing said part from said stop when the switch reaches a succeeding circuit controlling position whereby the pull operated means is returned to its initial position without affecting the switch. 50

6. In a pull switch having parts movable to circuit controlling positions, operating mechanism for moving said parts to successive circuit controlling positions including a rotatable member having symmetrically spaced notches in the 55 periphery thereof, pull operated means having a part adapted to engage one of said notches and positively rotate said member in either direction, means for returning the pull operated means to its initial position, means for holding said part 60 in engagement with said notch until said member has moved the switch to a succeeding circuit controlling position whereby upon release of the pull operated means prior to reaching the succeeding circuit controlling position said member 65 is positively returned by the pull operated means to the preceding position, and means for moving said part clear of said notch when the switch reaches a succeeding circuit controlling position whereby the pull operated means may be moved 70 toward and away from its initial position without affecting the switch.

7. In a pull switch having parts movable to circuit controlling positions, operating mechanism for moving said parts to successive circuit con- 75

5 controlling positions including a rotatable disk having symmetrically spaced notches in the periphery thereof, pull operated means having a part adapted to engage one of said notches and rotate said disk, means for returning the pull operated means to its initial position, means including a barrier for holding said part in engagement with said notch until the disk has moved the switch to a succeeding circuit controlling position whereby upon release of the pull operated means prior to reaching the succeeding circuit controlling position the disk is returned by the pull operated means to the preceding position, and means for releasing said part from said notch when the 10 switch reaches a succeeding circuit controlling position whereby the pull operated means is returned to its initial position without affecting the switch.

15 8. In a pull switch having parts movable to cir-

cuit controlling positions, operating mechanism for moving said parts to successive circuit controlling positions including a rotatable member, pull operated means having a part adapted to engage said member and thereby rotate said member, means including a barrier for holding said part in engagement with said member until said member has moved said switch to a succeeding circuit controlling position whereby upon release of the pull member prior to reaching the succeeding circuit controlling position the rotatable member is returned by the pull member to the preceding circuit controlling position, means for moving said part from between said barrier and said rotatable member when the switch has been 15 moved to a succeeding circuit controlling position, and means for returning said pull operated means to its initial position.

GEORGE R. BROWN.
